His Attorney.

UNITED STATES PATENT OFFICE

HAROLD J. WRAPE, OF ST. LOUIS, MISSOURI, ASSIGNOR, BY MESNE ASSIGNMENTS, TO BENWOOD-LINZE COMPANY, OF ST. LOUIS, MISSOURI, A CORPORATION OF MISSOURI

LEAD FOR RADIO SYSTEMS

Original application filed August 18, 1922, Serial No. 582,736. Divided and this application filed July 19, 1929. Serial No. 379,403.

The invention pertains to apparatus for use in wireless telegraphy and telephony.

This application is a division of application Serial No. 582,736, filed August 18, 1922.

5 In many installations of radio apparatus, condensers are required to furnish the required electrical capacity for proper tuning operations, adjustment of wave lengths, and similar purposes. In many cases the actual 10 value of the capacity required is extremely small, and values as low as 1/100 to 1/1000 of a microfarad being used. In such cases the dimensions of a condenser constructed for such small capacity become very small. In 15 fact, two parallel wires of several feet in length have been found to have between them sufficient capacity for some purposes.

One of the objects of this invention, therefore, is to provide a connecting lead for use 20 with radio apparatus which shall have incorporated therein a condenser of small capacity.

It is often found inconvenient or expensive 25 to erect the necessary antenna required for receiving or transmitting radio signals. In many cases it is found convenient to utilize in place of the antenna, an existing network of conductors such as, for instance, the electric light wiring of an ordinary house. Some 30 difficulty is encountered in connecting to the light wiring of an ordinary house, on account of the fact that such wiring is always connected to the service mains and the current from such mains must be kept out of the radio 35 apparatus.

Another object of this invention therefore is to provide a connecting lead or leads through which the radio set may be connected 40 to the house wiring as an antenna without interfering with the use of such wiring for its normal purpose.

Another object is to provide a convenient 45 form of connecting lead which may be attached to the house wiring by merely plugging into an ordinary lamp socket.

Further objects will appear from the following description taken in connection with the accompanying drawing, in which:

Fig. 1 is a diagram illustrating the general

method of connecting to the house wiring through leads embodying this invention.

Fig. 2 is a sectional view of a conductor embodying this invention.

Referring to the drawing, 1 designates a 55 lead which is made up of a pair of wires 2, each of which may be provided with its own insulation 3. The two insulated wires are enclosed in a common insulated covering 4 which may be provided at its ends with caps 60 5 to provide a closure therefor and to finish the end. One of the insulated conductors is arranged to protrude from each of the caps 5 and its protruding end is provided with a terminal 6 by means of which an electrical connection may be made thereto. In each conductor the end of the wire 2, opposite the terminal 6 is cut and insulated so as to be dead-ended. This end of the insulated conductor may be provided with a cap 7 to which 65 may be attached a flexible cord 8.

The conductors are mounted so that they 70 may slide in the covering 4 which may be a flexible covering. Thus either or both conductors may be drawn out of the covering by 75 pulling on the terminal end thereof and may be drawn back into the covering by drawing on the cord 8. In this way the lengths of wire of the two conductors which are adjacent to one another may be varied.

These adjacent lengths of wire provide a 80 condenser, the capacity of which varies in accordance with the lengths of conductors which are adjacent to each other. Accordingly a lead so constructed provides a condenser of small capacity and whose capacity 85 may be adjusted by drawing the conductors into or out of the covering 4.

In using this device the connection is made as illustrated in Figure 1, in which 9, designates the house wiring, 10 designates one coil of a radio transformer, of which 11 is the other coil. The coil 10 is connected to the main 9 through a pair of leads, 1, each lead comprising a pair of wires, 2. It will be 90 noted that one of each pair of wires 2, is connected to the mains, 9, while the other conductor, 2, of each pair is connected to the coil 10. It will be noted that there is thus no 95 conductive connection between the mains 9, 100

and the coil 10, so that practically none of the service current from the house circuit will flow through the coil, 10. Only such current as can pass through the condenser formed by the wires, 2, can flow and, since the voltage and frequency on the mains, 9, are comparatively very low, only a negligible current will flow from the mains through the coil 10.

The conditions that obtain with this connection, are however, very favorable for use in radio work. It will be understood that in ordinary house wiring one of the mains, 9, is grounded while the other is not. It will be evident, therefore, that by this connection one terminal of the coil, 10, will be connected through a light condenser to a network of wires adapted to provide an effective antenna. It is true that the grounded and ungrounded mains are connected together through the secondary coil of the service transformer. The inductance of such a coil is, however, so high that currents of radio frequently will not flow therethrough, so that the presence of such a coil will not affect the operation of the system for radio work.

While in the large majority of cases one side of the house wiring is grounded, there are some cases in which the house circuit is not grounded. In such case the radio set may be connected to one side of the house circuit by means of a single lead, and to the ground through a separate lead.

A convenient way to arrange for connection to the house circuit is to use a pair of leads such as shown in Fig. 2, and connect one terminal of each to a terminal of an ordinary plug such as may be inserted in an ordinary lamp socket. The other terminals of the leads are then connected to the radio set.

It will be evident from the foregoing that the invention accomplishes its objects. A device is provided whereby a radio set may be connected to the ordinary house mains in such a way that said mains will furnish both the ground connection and the antenna connection for the set. At the same time interference of the house circuit with the operation of the set is effectively prevented.

The connecting leads also furnish the required small value of capacity for ordinary radio sets, particularly amateur sets of which a great many are in use.

It is obvious that various changes may be made in the details of construction without departing from the spirit of this invention; it is therefore to be understood that this invention is not to be limited to the specific details shown and/or described.

Having thus described the invention, what is claimed is:

1. In a radio system, a lead comprising parallel filar conductors which are separated and arranged for relative adjustment in order to form a variable condenser.
2. In a radio system, a lead comprising

parallel filar conductors which are separated and arranged within a common covering, and means for effecting relative adjustment of said conductors in order to form a variable condenser.

3. In a radio system, a lead comprising parallel filar conductors which are separated and arranged within a common covering, and means for drawing said conductors into and out of said covering in order to form a variable condenser.

In testimony whereof I affix my signature this 26th day of June, 1929.

HAROLD J. WRAPE.
